UNITED STATES PATENT OFFICE

HOWARD P. DE CORREVONT, OF CHICAGO, ILLINOIS, ASSIGNOR TO THE BRUNSWICK-BALKE-COLLENDER COMPANY, OF CHICAGO, ILLINOIS, A CORPORATION OF DELAWARE

DESIGN FOR A TOILET-SEAT HINGE

Application filed December 17, 1928. Serial No. 29,302. Term of patent 14 years.

To all whom it may concern:

Be it known that I, HOWARD P. DE CORREVONT, a citizen of the United States, residing at Chicago, in the county of Cook and State of Illinois, have invented a new, original, and ornamental Design for Toilet-Seat Hinges, of which the following is a specification, reference being had to the accompanying drawing, forming part hereof.

Figs. 1, 2, and 3 are a side elevational, a rear elevational, and a plan view, respectively, of a toilet seat hinge showing my new design.

I claim:

The ornamental design for a toilet-seat hinge as shown.

In testimony whereof I hereunto subscribe my name.

HOWARD P. DE CORREVONT.
